UNITED STATES PATENT OFFICE

WALTER C. JOHNSON, OF JAMESTOWN, NEW YORK

ADJUSTABLE DIE

Application filed October 24, 1929. Serial No. 402,278.

This invention has relation to dies and particularly to dies intended and adapted for the formation of sheet metal panels, doors, partitions, ceilings and other articles 5 of similar character and has for its object the provision of novel means whereby the movable and stationary member may be adjusted to different sizes of panels, or sheet and whereby the shaping elements may be 10 changed to conform to the molding or edging of the sheets of metal to adapt the die to the production of different designs or marginal configurations or moldings.

My invention embodies and consists essentially in the novel construction of a die in which both the female and male members comprise each a plurality of sections or units which are adjustable and of which any required number may be used to enlarge or 20 diminish the size and capacity of the die, the components of each member consisting of adjustable corner sections and intermediate, interchangeable and detachable sections.

In the accompanying drawings illustrating a preferred embodiment of my improved die,

Figure 1 is a plan view with parts of the male members of the structure broken away to better illustrate the under parts;

30 Figure 2 is a vertical longitudinal section on the line 2—2 of Figure 1, showing the die members in relatively open position, with an intervening sheet to be pressed;

Figure 3 is a similar vertical longitudinal section, with certain details of the upper or male member omitted with the die members in closed relation and embracing a molded or pressed sheet;

Figure 4 is a plan view of the lower, stationary die member.

Figure 5 is a plan view of the adjustable retainer for the male die sections;

Figure 6 is an underside plan view of the upper die sections;

45 Figures 7 and 8 are sectional views of certain details;

Figure 9 is a perspective view of a filler element for the separable sections of the male die member.

50 The numeral 3 designates the base block of

the die, which is shown as being of oblong rectangular form, and which is provided on its upper surface with a plurality of horizontal under cut grooves or channels 4 extending inwardly from the edges of the block on all sides. The numeral 5 designates a set of retaining bars forming a frame or coping and arranged with the inner end of each bar abutting against the inner edge of an opposing bar and including a rectangular space which is adjustable in longitudinal and lateral directions to enlarge or diminish the size of the space.

Each bar is formed on its outer edge with a plurality of longitudinally slotted, lugs or flanges 6 for the passage of bolts 7 by which the bars are adjustably secured to the base block, the heads of the bolts being slidably disposed in the grooves or channels 4 of the base block and furnished with holding nuts 8.

Each of the bars 5 is adjustable both longitudinally and laterally, the lateral adjustment being provided for by the bolts 7 and grooves 4, and the longitudinal adjustment 75 through the slotted lugs 6 and bolts 7, the latter passing through the slots, and having the nuts 8 on their threaded ends above the flanges or ears 6. The bars 5 are formed on their inner edges with rebates 9 producing ledges for the seating of the die elements 10, which are correspondingly related and which are shaped on their inner edges to conform to the curvature of the borders of panels or other article to be formed by the die. The ends of the bars 5 will be coped or fashioned to rest snugly on the curved portions of the elements 10.

As will be noted, the upper surfaces of the bars 5 are serrated to prevent the blank 90 which is clamped thereon from slipping. The numeral 12 designates a series of retaining or clamping bars corresponding in shape and dimensions to the bars 5. These bars 12 are slotted longitudinally as indicated at 95 13, for the reception of bolts 14, which are carried by the plate 15 of the upper die member. This plate is slotted as shown at 16 for the passage of the bolts 14, the heads of which span the slots 16. The purpose of 100

these slots is to permit of the longitudinal and lateral adjustment of the bars 12 to correspond to the adjustment of the bars 5. Spiral springs 17 encircling the bolts 14 and located between the plate 15 and the bars 12 allow the bars 12 to be forced down into clamping relation with the bars 5 and the included blank 18 previous to the descent of the male die member.

10 The press plate 15 carries the die blocks 19, which are provided with dowel pins 19¹ fitting sockets 19² in the plate 15. There are a plurality of blocks 19 of rectangular form and assembled together to produce a male die combination corresponding in size to the female die combination. These blocks are removable and interchangeable so as to vary the dimensions of the die member to correspond to the adjustments of the lower die elements, to meet required changes as to size.

15 They are held together at their inner edges by dowel pins 19³ and receiving sockets so that they may be relatively spaced apart for the purposes of expansion. When so spaced, 20 the intervals between blocks may be filled by filling strips 24 corresponding to Fig. 9 and having bayonet slots 26 to interlock with the dowel pins 19³.

25 Where more than one panel is to be made 30 in a single blank the sections are removed from the upper die assemblage reversed and applied to the lower die.

35 The upper die member sections or blocks 19 have rebated lower outer corners to receive the curved members or edgings 9' which co-act with the complementary edgings of the lower die to produce the desired bending of the blank.

I claim:—

40 1. In a die of the character described, the combination with a base block of a set of retaining side and end bars, longitudinally and laterally adjustable relatively to said block and to each other, the end of each end bar abutting against the side of one side bar, and against the end of the opposite side bar whereby the enclosed rectangular space may be varied in dimensions in two directions while maintaining their contact relationship, the said bars and base constituting a lower member of a die press.

45 2. In a die as claimed in claim 1, a set of retaining bars laterally and longitudinally adjustable and carried by the upper member of the die press.

50 In testimony whereof I affix my signature.
WALTER C. JOHNSON.
